BASING APPARATUS

Filed Feb. 20, 1930

INVENTORS:

HENRIUS GOOSKENS,
JOHANNES M. J. POEL,

BY Charles E. Tullor

THEIR ATTORNEY

UNITED STATES PATENT OFFICE

HENRICUS GOOSKENS AND JOHANNES MARINUS VAN DER POEL, OF EINDHOVEN, NETHERLANDS, ASSIGNORS TO GENERAL ELECTRIC COMPANY, A CORPORATION OF NEW YORK

BASING APPARATUS

Application filed February 20, 1930, Serial No. 430,079, and in the Netherlands March 23, 1929.

Our invention relates to methods and apparatus for basing lamps and similar articles, and more particularly for performing the operation of threading the leading-in wires of the lamp through apertures in the base preliminary to soldering. The object of my invention is to eliminate the necessity for hand work in that operation.

According to our invention the lamp and base are placed in holders at opposite ends of the device and the leading-in wires extending from the lamp are located in an intermediate guide. The holders are then moved so that lamp and base are drawn toward each other while the leading-in wires are threaded through the base apertures by the guide. The guide is withdrawn before the lamp and base close upon each other. The specific device herein described is for use with the bayonet type of base as shown in the figures.

In the drawings, Fig. 1 is a side elevation of a machine constructed in accordance with our invention; Fig. 2 is a plan view of the lamp base, base holder and the leading-in wire guide; Figs. 3 to 7 inclusive are schematic drawings showing the various positions the wire guide, the lamp base and the lamp assume in their regular cycle of operation; and Fig. 8 is an end view of the lamp base, wire guide and leading-in wires when they are in the position shown in Fig. 5.

Referring now to the drawings, the incandescent lamp 10, complete except for the base, is held within the carriage 11 while its leading-in wires 12 rest in the grooves 13 of the wire guide 14. The lamp must rest in such position that the leading-in wires will be horizontally disposed or nearly so. The lamp base 15 rests within the holder 16 in such position that the holes 17 in the end thereof are lined up with the grooves 13 in the wire guide 14. When the base is inserted in the holder, one of the base pins 18 is placed in a depression in the base holder, thus definitely placing the holes in the base in the required position. The lamp base and lamp are then moved by the mechanism toward each other, from the position shown in Fig. 3 to that shown in Fig. 5. This operation slides the wires up the grooves 13 of the guide 14 and a substantial distance through the base holes 17. Further movement would be stopped by the guide 14 and is therefore delayed until the guide is withdrawn, as shown in Fig. 6. The further movement of the base and lamp bring them together and constitute the final operation of the machine.

The complete machine is driven by the longitudinal movement of the rod 19 which is operated by a suitable source. Such movement causes movement of the lamp carriage 11 and the cams 20 and 21 which in turn cause movement of the lamp, lamp base and wire guide. Over the face of the cam 20 rides the roller 22 of the lever 23 to which is attached spring 24 and which is carried by shaft 25. The variations in the cam surface encountered by the roller 22 causes partial rotation of the shaft 25. Rotation of that shaft swings lever 26 whose end engages the slot 27 of the base holder 16 and moves the holder and base carried thereby to the left of the figure. The wire guide 14 is moved by means of cam 21 which engages the roller 28 carried by lever 29 to which is attached spring 30. Lever 29 actuates shaft 31 carrying the lever 32 whose end engages a slot 33 in said guide and moves it downwardly to the left in the ways at the appropriate time to withdraw the guide, as shown in Fig. 6. This method of threading the wires through the holes in the base may also be applied to bases for radio tubes, rectifiers and similar articles. In such cases, it may be necessary to change the shape of the wire guide to take care of the desired number and arrangement of leading-in wires.

What we claim as new and desire to secure by Letters Patent of the United States is:

- An apparatus for inserting lead wires in bases comprising a bulb holder, a base holder, an intermediate wire guide, actuating means for causing said base holder and bulb holder to approach each other to cause said guide to enter said base, means

for subsequently withdrawing said guide and means whereby said withdrawing means is brought into operation by the operation of said actuating means.

- 5 2. An apparatus for inserting lead wires in bases comprising a bulb holder, a base holder, an intermediate wire guide, actuating means for causing said base holder and bulb holder to approach each other to cause said guide to enter said base, means for subsequently withdrawing said guide and positioning it out of line with said bulb and base and means whereby said withdrawing means is brought into operation by the operation of said actuating means;
- 10 3. An apparatus for threading lead wires in bases comprising a bulb holder, a base, actuating mechanism for causing said holders to approach each other, a movable guide having grooves at the outer end thereof mounted intermediate of said bulb and base holders and angularly disposed with reference to the line of movement thereof, means for withdrawing said guide when said bulb and base have reached definite positions and means whereby said withdrawing means is brought into operation by the operation of said actuating means.
- 15
- 20
- 25

In witness whereof, we have hereunto set
30 our hands this fourth day of February 1930.

HENRICUS GOOSKENS.

JOHANNES MARINUS van der POEL.
